UNITED STATES PATENT OFFICE.

HARRY S. McCORMACK, OF PROVIDENCE, RHODE ISLAND, ASSIGNOR TO
UNDERWOOD TYPEWRITER COMPANY, OF NEW YORK, N. Y., A COR-
PORATION OF NEW JERSEY.

TYPE-WRITING MACHINE.

No. 819,786.

Specification of Letters Patent.

Patented May 8, 1906.

Application filed February 16, 1905. Serial No. 245,918.

To all whom it may concern:

Be it known that I, HARRY S. McCORMACK, a citizen of the United States, residing in Providence, in the county of Providence and State of Rhode Island, have invented certain new and useful Improvements in Type-Writing Machines, of which the following is a specification.

This invention relates to the paper-feeding devices of type-writing machines; and its main object is to facilitate the recording of invoices or bills by the use of carbon-sheets in such a manner that carbon copies of several bills may succeed one another upon a single record-sheet, without, however, wasting the paper by leaving great spaces between the copies of the several bills. This operation is commonly known as "condensed charging," the bill, carbon, and record sheets being inserted in the machine together, the bill type-written and removed, the carbon and the record-sheet remaining in the machine, and a fresh bill being inserted and type-written and then removed, and so on, until the record-sheet is filled. It is usual to turn the platen backwardly, together with the record-sheet and carbon, to receive the new bill-head and then to turn the platen forwardly until it is in position for writing the first line upon the bill, which first line will properly succeed the lines theretofore written upon the record-sheet.

My improvements belong to the class of devices in which the platen may be rotated either by means of the usual line-spacing mechanism or by means of the usual platen knobs, either forwardly or backwardly, to an unlimited extent, while at any time, by manipulating a special crank, lever, or knob, the platen may be rotated back to receive a new bill and forwardly to bring the same to printing position, the limits of both backward and forward movements of the platen being mechanically determined.

One object of the present invention is to insure that blank spaces shall be left between successive entries upon the record-sheet or that proper line-spacing of the platen shall be made, so that after turning the platen back to receive a new bill and forward to bring the bill into writing position no attention need to be given by the operator to the matter of spacing between the bills, and still

there will be no liability of the first line of the second bill being written upon or over the last line of the first bill on the record-sheet, and the construction is preferably such that a blank line or space is left between such successive records, although this blank line may be omitted in some cases.

Another object is to enable the machine to accommodate bill-heads or the like in which a very great space is occupied at the top of the bill for the heading, and to this end I have contrived such a mechanism that by means of a single stroke of a crank the platen may be rotated backwardly more than an entire revolution and then forwardly to the starting-point, while at the same time the platen-stroke may be regulated to less than an entire revolution in order to suit short bill-heads.

Another object is to mount the crank or other manually-operable platen-rotating device so that said crank is convenient to the operator and clear of the remaining parts of the type-writing machine and may by a simple movement be not only connected to the platen, but also locked in such connection, or, in other words, the connection between the crank and the platen when once effected is maintained mechanically until the platen has been returned to a point slightly beyond its initial position, so as to produce the required spacing between successive records upon the record-sheet.

Other objects are to enable the platen-stop to be adjusted readily and accurately, to improve and simplify the construction and operation, and generally to improve the efficiency of the machine.

In the accompanying drawings, Figure 1 is a plan of a platen and a platen-frame of an "Underwood" type-writing machine, showing my improvements applied thereto. Fig. 2 is a front elevation of the right-hand portion of the platen and platen-frame, showing the platen-rotating crank normally disconnected from the platen and out of use. Fig. 3 is a part-sectional front elevation of a platen-driving gearing, showing the manner of mechanically maintaining the connection of the crank to the platen. Fig. 4 is a sectional elevation taken from front to rear at about the line X X of Fig. 1. Fig. 5 is an inverted sectional view taken at about the line Y Y of Fig.

3 and showing in working position a latch which serves as a temporary lock between the platen and the platen-driving crank when the latter is pressed down to effect connection with the platen. Fig. 6 shows the platen-driving crank and the parts directly fixed thereto. Fig. 7 is a view similar to Fig. 5, but showing the latch in normal ineffective position. Fig. 8 is a view similar to Fig. 7, but omitting the latch. Fig. 9 is a perspective view of the latch. Figs. 10 to 13 are perspective views illustrating the operation of the latch, &c., Fig. 10 showing the parts in normal position with the crank-gear in its elevated position of disuse, and the latch held out of working position by a foot which is provided upon said gear. Fig. 11 is similar to Fig. 10, but shows the crank-gear as having been depressed to become connected to the platen, and as being locked in its depressed position by the engagement of the latch with said foot. Fig. 12 is the same as Fig. 11, except that the gear has been rotated, (together with the platen,) said foot sliding in contact with a circular step or ring which is fixed to the platen-frame and concentric with said gear. Fig. 13 shows the gear rotated back to a point beyond its normal position (shown at Fig. 10)—that is, beyond the latch—the gear having now been elevated—by means provided for that purpose to normal position, from which position it is to be rotated by suitable means to the Fig. 10 position, forcing said latch out of the way, as in Fig. 10.

35 11 designates the usual cylindrical platen of an Underwood type-writing machine fixed upon an axle 12, journaled in a platen-frame 13, the ends of the axle projecting from the platen-frame and having finger-wheels 14 and 40 15 fixed thereon. By means of either finger-wheel the platen may be rotated forwardly or backwardly to an unlimited extent. The platen is also provided with the usual line-spacing devices, including a line-spacing 45 wheel 16, rigid with the platen and advanced intermittently by a pawl 17, which is operated in the usual manner by a slide 17^a and a lever 17^b, a spring-detent 17^c being employed to retain the line-space wheel by engaging 50 the notches thereof and being adapted to ride over the teeth 18, with which said wheel is usually provided.

Fixed upon the platen-axle 12 by means of a hub 19 is a bevel-pinion 20, having the same 55 number of teeth as the line-space wheel 16. Arranged horizontally over said pinion and normally out of mesh therewith is a bevel-gear or curved rack 21 of greater radius than the pinion 20, so that a partial revolution of 60 said gear may effect an entire or more than an entire revolution of said pinion and platen. Said gear 21 is fixed upon a vertical hub or shaft 22. Upon the top of the latter is fixed a crank 23 by means of a screw 24, said crank 65 having a manually-operable part or handle

25. The crank and gear are normally held up by means of a compression-spring 26, but may be pressed down at any time to bring said gear into mesh with said pinion, so that the crank may become enabled to rotate the 70 platen. Said shaft is hollow and works up and down upon a fixed vertical stud 27. The latter has at its lower end a head 28, perforated to fit loosely upon the platen-axle 12. Said head is confined between the hub 19 and 75 a washer 28, fixed upon said shaft. The upper end of the vertical crank-shaft 22 turns in a fixed bearing or hole 30, formed in a fixed horizontal plate 31, which may form part of the platen-frame 13, the latter being usually 80 mounted upon a carriage 32. It will be seen that said platen-frame comprises end pieces 33 and 34, upon the latter of which said plate 31 is fastened, while a vertical plate 35, similar to the end piece 34, is fixed upon said 85 platen-frame at the right-hand end of the platen and has a bearing 36 for the platen-axle similar to the bearing 37 upon the end piece 34. It will also be noticed that the horizontal plate 31 is secured by screws 38 to flanges 39, 90 formed upon said plates 34 and 35, thus forming a rigid structure. A tie-rod 40 extends horizontally through the plates 33, 34, and 35 and is rigidly connected to each, said tie-rod forming part of the usual structure of 95 the platen-frame of an Underwood type-writing machine. The spring 26 works between a shoulder 41, formed upon the lower end of said stud 27, and a shoulder 42, formed within 100 said crank-shaft 22.

Connection between the crank 23 and the platen 11 is maintained during the retraction of the platen by means of a foot 43, having the form of a lug fixed upon the upper face of the bevel-gear 21, said lug being adapted to 105 bear against a step or ring 44, which is concentric with the axis 22 of the bevel-gear, said step being formed or provided with a cylindrical support or body 45, having a flange 46, the latter being secured by screws 47 and 110 nuts or lugs 48 to the under side of the horizontal plate 31. Normally the foot or lug 43 occupies a recess 49, formed in the step or ring 44; but when the crank and gear are pressed down and rotated said foot rides 115 upon the under surface of the step 44, the platen of course being caused to turn or oscillate with the crank.

The return stroke of the crank is limited by a stop 50, fixed upon the plate 31; but the 120 forward stroke of the crank (which, it will be seen, effects a backward rotation of the platen) is limited by an adjustable stop 51, carried by an arm 52, that is pivoted loosely upon the crank-shaft 22 and confined by a 125 collar 53, fixed upon the latter, said arm 52 resting upon said plate 31. By means of this arm the stop may be swung to any desired position concentrically with the crank-shaft 22. To hold the stop where adjusted, 130

a circular rack 54 is provided concentric with said crank-shaft and consisting of a circular series or row of teeth 55, formed at intervals to agree with the teeth 18 of the line-spacing wheel 16. A rotative movement of the crank 23 through an arc equal to the distance from one tooth 55 to the next will effect a rotation of the platen equal to the distance from tooth to tooth 18 of said line-space wheel. Preferably the pinion 20 is materially smaller than the platen-wheel, the gear 21 twice the diameter of the pinion 20, and the radius of the rack 54 considerably greater than the radius of the gear 21. Said teeth or notches 55 are engageable by a tooth or detent 56, formed upon the end of a bar 57, pivoted at 58 to the arm 52, a spring 59 holding said detent in engagement with said rack or notches and said bar being provided with a finger-piece 60 for convenience in elevating the detent and moving it from point to point along said rack. By adjusting stop 51 in this way the stroke of the crank 23 and platen may be regulated to any desired extent between a slight platen movement and a rotation of considerably more than an entire revolution, and it will be understood that by varying the proportions of the gears it is practicable to effect a movement of the platen through even two revolutions or more, if desired, by a single vibration of the crank. In practicing, however, I have not found it necessary to extend the teeth 55 through more than about three-fourths of a circle, as seen at Fig. 1, this giving a stroke of about one and a half platen revolutions. The arm 52 is provided at its free end with a finger 61, which engages the opposite face of the rack from the teeth 55, a groove 62 being formed in the under side of the rack, into which said finger projects. The stop 51 may be set with accuracy by reference to a scale 63 upon the plate 31, the stop being provided with an index 64 to coöperate with said scale, each graduation of the scale corresponding with one line-space movement of the platen.

The member 43 upon the bevel-gear 21 serves not only as a foot, but also as a stop, being normally in engagement with the left-hand edge 64 of the recess 49 in the step, as seen at Fig. 2, at which time the gear 21 is in proper position to become properly enmeshed with the pinion 20 by means of a vertical downward movement of the gear and 55 without any disturbance of the pinion or platen, and as a result the pinion may be moved by the gear through an arc exactly predetermined by the position of the stop 51, and equal to a predetermined number of line-spaces without liability of error. Bearing normally against the inner side of said foot is a latch 65, pivoted at 66 within the cylindrical support 45 and lying between the step 44 and the plate 31 and provided with a spring 67. The function of this latch is to vibrate

outwardly over the top of the foot 43 whenever the latter moves down, thereby latching the gear down in mesh with the pinion. The normal position of the latch is seen at Figs. 7 and 10, at which figure the other parts are in the same position as at Fig. 2. At Figs. 3 and 11 it will be seen that the gear has been depressed, thus permitting the latch to be swung outwardly by the spring 67, as at Figs. 11 and 5. The latch now occupies a position over the foot 43 and prevents the latter from rising. Thus it will be seen that by simply pressing down the crank 23 the gear 21 is connected properly with the pinion 20 and locked in mesh. When the crank is 80 swung toward the left, said foot 43 contacts with the step 44, as seen at Fig. 12. Upon the return stroke of the crank when the foot 43 reaches the initial rotative position seen at Fig. 11 the foot is again prevented by the latch from rising. Since, however, the crank has not yet reached the fixed stop 50, the backward movement of the crank is continued, so that the foot is carried back past the head 65 of the latch. Then the foot trips off the latch and is thrown upwardly by the spring 26, together with the gear and crank. The latter is at this time in contact with the stop 50, as at Figs. 1 and 4, and the foot 43 occupies a notch 68, formed in the latch. 90

The dimensions of the foot and latch are such that during the backward movement past the latch the platen is rotated preferably two line-spaces, and hence the forward stroke is made greater by two line-spaces than the rearward stroke thereof, so that the record-sheet is advanced automatically two line-spaces, insuring that the first line of the new bill shall not be written over or upon the last line of the preceding record. Upon releasing the crank the latter is given a start forward by means of a spring-finger 69, which is fixed upon the crank-shaft 22 by means of a screw 70 and projects therefrom to a position for engaging a lug 71, fixed upon the under side of the plate 31. This spring rotates idly with said crank-shaft, as at Fig. 12; but at the latter part of the return movement of said shaft the spring engages said lug 71 and is thereby put under sufficient tension so that when the crank is released from the control of the operator the spring retracts the shaft, gear, and crank until the foot or stop 43 reaches the normal position. (Seen at Fig. 2.) Thus the initial part of the forward movement of the crank between the stops 50 and 51 is effected without turning the platen, but the platen is rotated throughout the entire return movement of the crank, with the result already given of feeding the record-sheet forward two extra line-spaces. During this initial movement effected by spring 69 the foot 43 engages an inclined face 65^b of the latch and cams the latter to normal position, (Seen at Fig. 10.) 125

The screws 47 pass through slots 72 and the plate 31, said slots being concentric with the crank-shaft and of sufficient length to permit slight circular adjustment of the rack 54 to enable the vertical edge or stop 64 to be adjusted slightly, so that the gear 21 may be caused to stand normally in accurate relation with the pinion 20, thus insuring that the gear shall move accurately into mesh with the pinion when the gear is pressed down. I also prefer to provide a second series of four slots 73 in the same circular line with the slots 72, thereby enabling a substantial change in the adjustment of the stop or edge 64 to be made, if desired.

The record-sheet, bill, and interleaved carbon may be inserted together between the platen 11 and the usual paper-shelf. They are then carried around by the usual pressure-rolls 74 until the proper blank line upon the bill is brought to the printing-point. The bill is then written line by line, the usual line-spacing devices being employed to advance the sheets until the last line is written. Thereupon the pressure-roller-release mechanism 75 may be operated to cast off the rollers 74 in the usual manner, and the bill may then be withdrawn by pulling it up in the front of the platen, while the record and carbon sheets remain in the machine undisturbed. The mechanism 75 is then permitted to return to normal position, and the operator depresses the crank 23 and pulls it forwardly as far as it will go. By this operation the carbon and record sheets are rolled back for a distance equal to the space occupied by the printed matter on the bill-head. Then a fresh bill is inserted and the crank is turned back as far as it will go, being arrested by the stop 50, and the spring 26 serving to disengage the gear 21 from the pinion 20, thereby permitting free rotation of the platen in either direction. By the last movement of the crank the fresh bill is brought to the front of the platen and is then written, the carbon copy thereof succeeding the copy of the first-written bill upon the record-sheet, a blank line appearing between the successive records. The second bill may then be withdrawn and a fresh bill inserted in the described manner and the operations repeated for successive bills until the record-sheet is filled.

The position to which the stop 51 should be set may be determined by first inserting a bill (or letter-head) in the machine and turning the platen until the first writing-line on the bill reaches the printing-point. Then the platen is turned backwardly by means of the crank until the bill passes back of the usual rear feed-roll, and hence is released from the machine. When the crank is at this point, the stop 51 is set so that the stroke of the crank thereafter shall be the same length as the stroke just made.

Upon adjusting the ring or step 44 circumferentially, so that the slots 73 are brought into use, it is necessary to readjust the circular rack 54 also, so that the fixed stop 50 upon the latter may be brought into the proper relation with stop 64. To adjust the circular rack 54, it is only necessary to take out the screws 75, which secure it upon the plate 31, and upon turning the rack around the screws may be again used to secure the rack as readjusted. For this purpose a sufficient number of screws 75 should be employed and placed at such intervals as to permit the desired adjustment.

By reversing the pinion 20 upon the platen-axle 12 and placing it just beneath the left-hand portion of the gear 21 at Fig. 2 the first stroke of the crank 23 can be made to give the platen a backward rotation and the return stroke of the crank will turn the platen forwardly. Other variations may be resorted to within the scope of my invention and portions of my improvements may be used without others.

Having thus described my invention, I claim—

1. In a type-writing machine, the combination with a revoluble platen, a line-space wheel, and a platen-frame, of stops, means coöperating with the stops for arresting both the forward and backward revolutions of the platen; said stops being relatively adjustable to an extent to limit the movement of the platen to either more or less than an entire revolution at will, and means whereby said stops are normally silenced so that the platen may be rotated indefinitely in either direction independently of the stops.

2. In a type-writing machine, the combination with a platen, a line-space wheel, and a platen-frame, said platen being normally revoluble at will in either direction to an unlimited extent, of a manually-operable device for rotating the platen both forwardly and backwardly, and stops to coöperate with said manually-operable device for limiting the forward and backward revolution of the platen to predetermined numbers of line-spaces; said stops being relatively adjustable to an extent to limit the movement of the platen to either more or less than an entire revolution at will.

3. In a type-writing machine, the combination with a revoluble platen, of stops for arresting both the forward and backward revolutions of the platen; said platen being normally revoluble at will in either direction to an unlimited extent independently of said stops, and means being provided for rendering said stops effective at will; said stops being relatively adjustable to an extent to limit the movement of the platen to either more or less than an entire revolution.

4. In a type-writing machine, the combination with a revoluble platen provided with

- a pinion, of a rack to mesh with said pinion and capable by a single stroke of rotating the platen in either direction through more than an entire revolution, a finger-piece connected to said rack, means for effecting at will an operative connection between said finger-piece and platen through said rack and pinion, and relatively adjustable stops for limiting the stroke of said rack.
10. 5. A revoluble type-writer platen provided with a finger-wheel whereby it may be rotated in either direction at will to an unlimited extent, and also provided with a manually-operable contrivance whereby the platen may be rotated in either direction at any time through an arc of predetermined extent either less or more than an entire revolution, the limits of such arc being determined by mechanical means.
20. 6. In a type-writing machine, the combination with a revoluble platen and line-spacing mechanism therefor, of a pinion connected to the platen, and a larger gear normally disengaged from said pinion; means being provided for effecting engagement between said gear and pinion at will, and relatively adjustable stops being provided for limiting the movements of said gear forwardly and backwardly.
30. 7. In a type-writing machine, the combination with a platen and its axle, of a bevel-pinion upon said axle, a larger bevel-gear normally out of mesh with said pinion, means for holding said gear in mesh with said pinion, and stops for limiting the rotation of said bevel-gear.
40. 8. In a type-writing machine, the combination with a platen, of a bevel-pinion concentric therewith and connected thereto, a bevel-gear normally out of mesh with said pinion, means for enabling said gear to move into mesh with said pinion, a finger-piece for said gear, and relatively adjustable stops for limiting the rotation of said bevel-gear.
45. 9. In a front-strike writing-machine, the combination with a platen and platen-frame, of a pinion concentric with the platen and connected thereto, a larger gear overlying said pinion with its axis transverse to the pinion-axis and normally out of mesh with the pinion, a finger-piece or crank connected to said gear, a circular rack concentric with said gear, a stop adjustable along said rack for arresting said gear, and means for enabling said gear and pinion to mesh.
55. 10. In a type-writing machine, the combination with a revoluble platen, of a finger-piece or crank mounted for rotation, relatively adjustable stops for limiting the stroke of said finger-piece, and means, including movement-multiplying gearing, for connecting or disconnecting said platen from said finger-piece and stops at will; said stops being relatively adjustable to an extent to limit the movement of the platen to either more or less than an entire revolution at will.
11. In a type-writing machine, the combination with a revoluble platen, of a crank or finger-piece mounted for rotation, relatively adjustable stops for limiting the stroke of said finger-piece in both directions, and means, including movement-multiplying gearing, for positively connecting said finger-piece at will to said platen so as to enable the finger-piece to rotate the platen both forwardly and backwardly.
12. In a type-writing machine, the combination with a platen and a line-space wheel, of a pair of normally disengaged gears whereof one is connected to the platen and the other is provided with a finger-piece, means for effecting the engagement of said gears at will, a stop for limiting the movement of the platen by means of said gear, and means for mechanically maintaining the engagement of said gears until the forward and backward strokes of the platen effected thereby are completed.
13. In a type-writing machine, the combination with a platen and a line-space wheel, of a pair of gears one connected to the platen and the other provided with a finger-piece, said gears being normally out of engagement; means for locking said gears in engagement, a stop to limit the movement of the platen effected by said gears, and means rendered effective by the return stroke of the gears, for releasing said locking means.
14. In a type-writing machine, the combination with a platen and a line-space wheel, of a pair of gears normally out of engagement, one gear being connected to the platen and the other being provided with a finger-piece, one of said gears being movable into mesh with the other, a step for said movable gear, and a foot which may bear upon said step to maintain the engagement of said gears during the platen movement effected thereby.
15. In a type-writing machine, the combination with a platen, of a pair of normally disengaged gears, one thereof being connected to the platen and the other provided with a finger-piece, one of said gears being movable axially to mesh with the other, and fixed step, and a foot upon said movable gear for bearing upon said step to maintain the engagement of said gears, said step having a depression to receive said foot when the gears are out of mesh, and a spring for holding said gears out of mesh.
16. In a type-writing machine, the combination with a platen, a platen-axle, and a line-space wheel, of a pair of relatively movable bevel-gears, said gears being normally out of engagement and one thereof mounted upon the platen-axle, a finger-piece connected to the other of said gears, relatively adjustable stops for limiting the forward and

- backward strokes of the platen by means of said gears, and means for mechanically maintaining the engagement of said gears during strokes of the platen and disengaging 5 said gears at the completion of the platen movement.
17. In a type-writing machine, the combination with a platen and a line-space wheel, of normally disengaged clutch-wheels, a 10 spring tending to maintain the disengagement of said clutch-wheels, means rendered effective by a clutching movement of one of said wheels for holding said wheels in engagement, and stops for limiting the strokes of 15 the platen effected by said clutch-wheels.
18. In a type-writing machine, the combination with a platen and a platen-frame, of a 20 crank mounted upon the platen-frame to swing in a horizontal plane, means, including a pair of bevel-gears, for connecting the crank to the platen at will, and stops for limiting the movements of the crank.
19. In a type-writing machine, the combination with a platen and a platen-frame, of a 25 crank mounted upon the right-hand end of the platen-frame to swing in a horizontal plane, the platen being freely revoluble forwardly and backwardly independently of said crank, stops for limiting the strokes of 30 said crank, and means, including a pair of bevel-gears, for connecting the crank to the platen at will and mechanically maintaining such connection during the backward and forward strokes of the crank between said 35 stops.
20. In a type-writing machine the combination with a revoluble platen and a platen-frame, of a crank normally disconnected from the platen, means, including a bevel-pinion 40 and a bevel-gear, for connecting the platen to the crank at will, and stops for limiting the forward and backward strokes of the crank.
21. In a type-writing machine, the combination with a platen, a platen-axle and a 45 platen-frame, of a bevel-pinion mounted upon said platen-axle, a downwardly-movable horizontal bevel-gear mounted over said axle, a spring for lifting said gear out of engagement with said pinion, a shaft upon said 50 gear, a crank fixed upon the upper end of said shaft, relatively adjustable stops for limiting the strokes of said crank, a step overlying said gear and having a recess, and a foot upon said gear and normally occupying said 55 recess.
22. In a type-writing machine, the combination with a platen and a line-space wheel, of a crank normally disconnected from the platen, relatively adjustable stops for limiting 60 the forward and backward strokes of said crank, and means rendered effective by the movement of the crank in one direction for connecting it to the platen, so that the platen can be rotated by movement of the 65 crank in another direction.
23. In a type-writing machine, the combination with a platen, a line-space wheel and a platen-frame, of a crank mounted to swing horizontally upon the platen-frame, and means rendered effective by downward pressure upon the crank to connect the same with the platen, releasable means for mechanically maintaining connection between the crank and the platen, and stops for limiting the strokes of the crank. 7c
24. In a type-writing machine, the combination with a platen and a platen-frame, of a crank mounted upon the platen-frame and normally disconnected from the platen, means for connecting the crank to the platen at will in such a manner that rotation of a crank effects greater angular rotation of the platen, and means for limiting the movement of the crank. 7s
25. In a type-writing machine, the combination with a platen and a platen-frame, of a crank mounted upon the platen-frame and normally disconnected from the platen, means for connecting the crank to the platen at will in such a manner that the rotation of the crank effects greater angular rotation of the platen, means for limiting the movement of the crank, and means for mechanically maintaining the connection, and finally effecting the release of the platen from the control of the crank upon the return of the latter to normal position. 85
26. In a type-writing machine, the combination with a platen, of normally disengaged gears, means for effecting and maintaining engagement of the gears, means, including relatively adjustable stops co-operating with said gears, for effecting backward and forward rotation of the platen through predetermined arcs. 90
27. In a type-writing machine, the combination with a platen and a line-space wheel, of a crank normally disconnected from the platen and locked against rotation, means operable by a movement of the crank in axial direction for releasing the crank so that it may rotate, and for connecting the crank to the platen, and stops for limiting the forward and backward rotation of the crank. 105
28. In a type-writing machine, the combination with a platen and a line-space wheel, of a crank normally disconnected from the platen and locked against rotation, means operable by a movement of the crank in axial direction for releasing the crank so that it may rotate, and for connecting the crank to the platen, and temporarily maintaining such connection, a stop for limiting the movement of the crank and means dependent upon the turning of the crank, for mechanically releasing the platen from the control of said crank. 110
29. In a type-writing machine, the combination with a platen and a line-space wheel, of a horizontally-swinging crank normally 125

disconnected from the platen and locked against rotation in either direction, means for releasing the crank so that it may rotate and for connecting the crank to the platen 5 temporarily maintaining such connection, stops for limiting the forward and backward rotation of the crank, and means for mechanically releasing the platen from the control of said crank at the completion of the 10 return swing of the latter to normal position.

30. In a type-writing machine, the combination with a revoluble platen, of a manually-operable device, means, including a 15 pair of gears, for connecting said manually-operable device to the platen to rotate the outer either forwardly or backwardly, stops for limiting the strokes of said manually-operable device in forward and backward 20 direction, means for mechanically maintaining the connection between said platen and said manually-operable device during the reciprocation of the latter between said stops, and line-space mechanism, whereby said 25 platen may be rotated indefinitely independently of said stops.

31. In a type-writing machine, the combination with a platen and a line-spacing mechanism therefor, of a normally released clutch 30 capable of rotating the platen in either direction, stops for limiting the rotation of such clutch in each direction, and means for mechanically maintaining the engagement of said clutch during the movements of the 35 platen which are limited by said stops; said clutch being in the form of a pair of gears which are relatively movable into and out of engagement.

32. In a type-writing machine, the combination with a revoluble platen, of normally ineffective stops for arresting both the forward and backward revolutions of the platen, a crank, and normally inoperative means, including movement-multiplying gearing, for 45 enabling said crank to rotate said platen and render said stops effective.

33. In a type-writing machine, the combination with a revoluble platen and line-spacing mechanism therefor, of a pinion connected to the platen, a larger gear to drive said pinion, means for limiting the rotation of said driving-gear in each direction, and means for silencing said gears.

34. In a type-writing machine, the combination with a platen and a platen-frame, of a crank mounted upon the platen-frame, a circular rack concentric with the axis of said crank, stops at least one of which is adjustable along the rack, and means, including 50 normally disengaged movement-multiplying gears, for connecting said crank to said platen.

35. In a type-writing machine, the combination with a revoluble platen, a line-space 55 wheel and a platen-frame, of a crank mount-

ed upon the platen-frame, a circular rack concentric with the axis of said crank, a stop adjustable along said rack, and means, including movement-multiplying devices, for connecting said crank at will to the platen, the teeth of said rack being at intervals to agree with the line-spacing movements of the platen.

36. In a type-writing machine, the combination with a revoluble platen and line-space mechanism, of a hand-wheel for rotating the platen an unlimited distance in either direction at will, and means, including co-operative stops, for rotating said platen either forward or backward at will through a predetermined arc either less or greater than an entire revolution of the platen, regardless of the position to which said platen may have been adjusted by said hand-wheel.

37. In a type-writing machine, the combination with a revoluble platen, a line-spacing wheel and a platen-frame, of a normally ineffective crank, multiplying gear between said crank and said platen, means for rendering said crank effective, and stops for limiting to a predetermined number of line-spaces the forward and backward revolutions of the platen effected by said crank.

38. In a type-writing machine, the combination with a revoluble platen, and a line-spacing mechanism therefor, of a crank, a normally disengaged pair of clutch-wheels between said crank and said platen; said crank being movable in one direction to effect the engagement of said wheels, and in another direction to effect the rotation of said wheels, and stops for limiting the movement of said wheels in each direction.

39. In a type-writing machine, the combination with a revoluble platen, of normally ineffective stops for arresting both forward and backward revolutions of the platen, a crank capable of both turning the platen in either direction more than an entire revolution and rendering such stops effective, and means normally locking said crank against rotation in either direction.

40. In a type-writing machine, the combination with a revoluble platen, and line-spacing mechanism therefor, of a normally released clutch capable of rotating the platen more than an entire revolution in either direction, stops for limiting the movement of clutch in each direction, said clutch comprising two members, one of which is connected to the platen, and means normally locking the other member against rotation.

41. In a type-writing machine, the combination with a platen and platen-frame, of a crank, a pair of normally disengaged gears, one connected to said crank and the other to said platen, and means normally locking against rotation, said crank-gear.

42. In a type-writing machine, the combi-

nation with a platen, a platen-axle, and a platen-frame, of a bevel-pinion mounted upon the platen-axle, a bevel-gear normally out of mesh with said pinion and mounted upon the 5 platen-frame and having a hub or shaft, a crank upon said shaft, a spring whereby said gear is held out of mesh with said pinion, relatively adjustable stops for limiting the forward and backward strokes of said crank, and means rendered effective by the movement of said gear into mesh with said pinion, for maintaining such engagement during the forward and backward strokes of the crank.

43. In a type-writing machine, the combination with a platen and a platen-frame, of a crank upon the platen-frame, at one end thereof and mounted to swing horizontally, relatively adjustable stops for limiting the forward and backward strokes of said crank; 20 the platen being revoluble independently of said crank; means rendered effective by vertical pressure upon the said crank to connect the same with the platen, and means for maintaining such connection during the forward and backward strokes of the crank.

44. In a type-writing machine, the combination with a platen and a platen-frame, of a circular rack mounted upon the platen-frame, a crank mounted concentrically with said circular rack, stops for said crank, one of said stops being adjustable along said rack, and a pair of normally ineffective movement-multiplying bevel-gears for connecting said crank at will to said platen; said stops being relatively adjustable so as to limit the throw of the platen to a predetermined number of line-spaces either less or greater than an entire revolution of the platen.

45. In a type-writing machine, the combination with a platen, of a member capable of mechanically-limited oscillation, and connectible to the platen at will, and adjustable means for mechanically limiting the extent of forward and backward rotation of the 45 platen to either more or less than a complete revolution at will.

46. In a type-writing machine, a platen a normally disconnected manually-operable device for rotating the platen, means for connecting said manually-operable device to the platen at will, and stops for limiting the forward and backward strokes of said manually-operable device, in combination with means for causing the backward strokes to be 55 shorter than forward strokes of the platen effected by the reciprocation of said manually-operable device between said stops.

47. In a type-writing machine, a revoluble platen, a line-space wheel, a platen-frame, 60 and relatively adjustable stops for arresting both forward and backward revolutions of the platen, in combination with mechanism which causes the forward stroke to be greater than the backward stroke of said platen between said stops, for the purpose specified.

48. In a type-writing machine, the combination with a platen, of a platen-frame, a manually-operable device for rotating the platen, stops for limiting the forward and backward strokes of the platen, and means for causing the initial portion of the platen-retracting movement of said manually-operable device between said stops to be ineffective, for the purpose specified.

49. In a type-writing machine, the combination with a revoluble platen of a normally disconnected manually-operable device for rotating the platen forward and backward, stops limiting the strokes of said manually-operable device, means for connecting said manually-operable device to the platen, means rendered effective by the completion of the platen-advancing stroke of said manually-operable device for disconnecting the manually-operable device from the platen, and means for mechanically effecting a slight movement of said manually-operable device while so disconnected, in the direction of the platen-retracting stroke of said manually-operable device.

50. In a type-writing machine, the combination with a platen and a manually-operable rotative device movable axially and normally disconnected from the platen, of means for enabling an axial movement of said rotative device to connect the latter to the platen, a foot upon said rotative device, a latch engaging said foot to lock said rotative device in connection with the platen, a step for maintaining such connection during the rotation of the platen forwardly and backwardly by said rotative device; said step having a recess normally occupied by said foot, and a spring for effecting the return axial movement of said rotative device.

51. In a type-writing machine, the combination with a platen and a manually-operable rotative device movable axially and normally disconnected from the platen, of means for enabling an axial movement of said rotative device to connect the latter to the platen, a foot upon said rotative device, a latch engaging said foot to lock said device in connection with the platen, a step for maintaining such connection during the rotation of the 115 platen forwardly and backwardly by said rotative device; said step having a recess normally occupied by said foot, and a spring for effecting the return axial movement of said rotative device, and a spring for rotating said rotative device slightly in the platen-retracting direction, while disconnected from the platen.

52. In a type-writing machine, the combination with a revoluble platen, of a pinion 125 connected to the platen, a gear normally disengaged from said pinion, means for effecting engagement between said gear and said pinion at will, relatively adjustable stops for limiting the movement of said gear and 130

- platen forwardly and backwardly, and means for mechanically maintaining said gear in mesh for a greater platen-advancing than platen-retracting movement.
- 5 53. In a type-writing machine, the combination with a platen and its axle, of a bevel-pinion upon said axle, a bevel-gear normally out of mesh with said pinion, means permitting movement of said gear into mesh with the pinion, stops for limiting the rotation backward and forward of said bevel-gear, and means for mechanically holding said gear in mesh with said pinion longer during the platen - advancing stroke than during the 15 platen - retracting stroke, for the purpose specified.
54. In a type-writing machine, the combination with a platen, of a platen-rotating gear normally disconnected from the platen, 20 a foot provided upon said gear, a spring for keeping said gear in normally disconnected position, a pinion connected to the platen, said gear being movable axially into mesh with said pinion, a normally idle latch which 25 engages said foot to maintain such mesh, and a step coincident with said latch and against which said foot may bear during the rotation of said gear and platen.
55. In a type-writing machine, the combination with a platen, of a platen-rotating gear normally disconnected from the platen, a foot for said gear, a pinion connected to the platen, said gear being movable into mesh with said pinion, a normally idle latch which 30 35 engages said foot to maintain such mesh, a step coincident with said latch and against which said foot may bear during the rotation of said gear and platen; said foot being movable past said latch upon the return stroke of the gear and platen; and a stop for limiting the return stroke of said gear.
56. In a type-writing machine, the combination with a platen, of a platen-rotating gear normally disconnected from the platen, 40 a foot for said gear, a spring for keeping said gear in normally disconnected position, a pinion connected to the platen, said gear being movable axially into mesh with said pinion, a normally idle latch which engages said foot 45 50 to maintain such mesh a step coincident with said latch and against which said foot may bear during the rotation of said gear and platen; said foot being movable past said latch upon the return stroke of the gear and platen; and a stop for limiting the return stroke of said gear; said latch being movable
- to normal idle position by a forward rotation of said foot.
57. In a type-writing machine, the combination with a platen, of a platen-rotating gear normally disconnected from the platen, 55 a foot for said gear, a spring for keeping said gear in normally disconnected position, a pinion connected to the platen, said gear being movable axially into mesh with said pinion, a normally idle latch which engages said foot to maintain such mesh a step coincident with said latch and against which said foot may bear during the rotation of said gear and platen; said foot being movable past said 60 latch upon the return stroke of the gear and platen; and a stop for limiting the return stroke of said gear; said latch being movable to normal idle position by a forward rotation of said foot, a spring for effecting sufficient 65 forward movement of the gear to enable said foot to press said latch to normal position, and a stop for limiting such movement of the gear.
58. In a type-writing machine, the combination with a platen, of a manually-operable 70 device normally disconnected from the platen, means for connecting said device to the platen, stops for limiting the forward and backward strokes of said manually-operable device, a rack along which one of said stops is 75 adjustable, an arm whereon said adjustable stop is pivoted, said arm being pivoted concentrically with said manually-operable device, and said stop having a tooth to engage said rack, a spring for maintaining engagement of said tooth with said rack, and an arm 80 having a finger to engage said rack on the opposite side thereof from said stop.
59. In a type-writing machine, the combination with a platen and a platen-frame, of a 85 normally disconnected manually-operable device for rotating the platen, means for connecting said manually-operable device to the platen at will, stops for limiting the forward and backward movements of said manually-operable device, a rack fixed upon the framework of the carriage upon which said stops are 90 mounted and means for enabling circular adjustment of said rack and stops; said adjusting means including a set of screws which hold 95 the rack upon the carriage, and said rack being provided with two sets of concentric slots either set of which may receive said screws.
